United States Patent Office.

THOMAS F. CONNER, OF ODIN, ILLINOIS.

Letters Patent No. 69,972, dated October 22, 1867.

IMPROVED CAR-COUPING.

The Schedule referred to in these Letters Patent and making part of the same.

TO ALL WHOM IT MAY CONCERN:

Be it known that I, THOMAS F. CONNER, of Odin, Marion county, State of Illinois, have invented a new and useful Improved Car-Coupling, of which the following is a full, clear, and exact description, reference being had to the annexed drawing, making a part of this specification, in which—

Figure 1 represents a side elevation of two of my couplings, with the side plates removed, showing the arrow-headed draw-bars.

Figure 2 represents a side elevation of one of my couplings, with the side plate removed, and an old-style coupling, showing the hook of my coupling.

Figure 3 represents a top view of one of my arrow-headed draw-bars and hook.

Similar letters indicate like parts.

My invention contemplates a car-coupling which shall couple automatically, and be uncoupled without requiring any one to go between the cars.

It consists of two arrow-headed draw-bars A A', fig. 1, and A', figs. 2 and 3, coupling on to the back or top of each other by the following operations: A car provided with my coupling being backed down upon another having my invention attached, both of the draw-bars resting upon the pins b b', fig. 1, and b, fig. 2, the car having the higher draw-bar will make the coupling, as shown in fig. 1. The draw-bar A being the higher, its point will strike the top of the draw-bar A', and slide up, moving the pawl c back past the same, which will then drop behind the shoulder e of the arrow-head, firmly locking the coupling. Had the car bearing the draw-bar A' been the higher the operation would have been reversed, the arrow-head A' then passing on top of the other, and being locked by the pawl c'. It is not necessary that one draw-bar should be greatly higher than the other, since, if there is any difference in height, the arrow shape of the heads will insure the one slipping on top of the other. In order to unlock the coupling, the draw-head is provided with a crank, d d', fig. 1, and lifting-rods e e' attached, which rod and crank, when lifted, will release the arrow-head. And further to insure the perfect freedom of the arrow-heads when unlocked to glide off, the under portion of same is bevelled, as shown at f f', fig. 1, and f', fig. 2, whilst the coupling is insured by rounding the edges of the side plates and chamfering the edge of the arrow-heads, as shown at h, fig. 3, so that should the cars come together at an angle the draw-heads will nevertheless glide to their proper places. The pawl and rod, being of iron, will by their own weight fall so that the crank will be perpendicular; but the pawl being keyed on the shaft at a slight angle, when the arrow-head makes the coupling and comes up to a horizontal position, will be lifted, instead of tripping the arrow-head down, as it otherwise might. In order that a car with my coupling may unite with one of the old style, I construct my draw-bar with a slot, from the heel to within a short distance of the head, and have a hook, k k', fig. 1, and k, figs. 2 and 3, playing freely in the same, which can by means of the hand be made to catch the link of the common coupling, as shown at m, fig. 2, and may be uncoupled in the same manner.

The advantages of my invention consist, as shown above, in the facility and certainty with which cars, whether of the same or different heights, can be coupled automatically, and uncoupled without exposing the operator to the danger of going between the cars. The advantage of this is seen particularly when it is desired to couple on to a "foreign" car. Unlike other automatic couplings, mine will work equally well when cars approach at an angle, on account of the beveling and chamfering described above, and the great play given the draw-bars by reason of their length. The free play which the bars have will obviate the danger of uncoupling on account of the jumping of the cars while in motion, which is a great defect in most self-couplings. The length of the hook and the consequent play given it render it superior to the old method of coupling.

I do not claim to be the first inventor of an automatic car-coupling, nor of the use of arrow-headed draw-bars; but what I do claim as my invention, and desire to secure by Letters Patent, is—

1. The arrow-heads A A', the hooks k k', the cranks d d', the lifting-rods e e', the pawls c c', and side plates R R', all in combination, when constructed and arranged substantially as shown and specified.

2. The construction of the slotted draw-bar A, in combination with the hook k, when constructed and arranged substantially as shown and specified.

T. F. CONNER.
